UNITED STATES PATENT OFFICE.

GUSTAVUS A. WAGNER, OF JASPER, MICHIGAN.

FORMER OR MOLD FOR FORMING CONCRETE CISTERNS.

1,029,646.

Specification of Letters Patent.

Patented June 18, 1912.

Application filed March 11, 1911. Serial No. 613,689.

To all whom it may concern:

Be it known that I, GUSTAVUS A. WAGNER, citizen of the United States, residing at Jasper, in the county of Lenawee and State of Michigan, have invented certain new and useful Improvements in Formers or Molds for Forming Concrete Cisterns, of which the following is a specification.

My invention has relation to improvements in sectional and collapsible formers for forming cylindrical concrete or cement cisterns of that class commonly known as "jug cisterns," and it has for its object primarily to provide by the peculiar construction of the former an opening in the neck portion of the same considerably smaller in diameter than that of the body portion through the medium of said opening.

The sections of the former can be readily and conveniently taken apart piece by piece and withdrawn through the opening after the cistern is set or hardened and the sections can be again assembled through the opening for forming the cistern.

With this and other objects in view the invention consists in the novel construction and combination of parts as will be herein-after more in detail described and the asserted novelty specifically claimed.

I have fully and clearly illustrated my invention in the accompanying drawings in which;

Figure 1 is a central vertical section of my former in which is shown the sections and parts assembled after it is located in an opening formed in the ground for forming the cistern. Fig. 2 is a cross section on the line $x-x$ of Fig. 1. Fig. 3 is a bottom plan view of the cover. Fig. 4 is a detail view of one of the side sections of the former. Fig. 5 is a detail top or plan view of side section. Fig. 6 is a detail bottom plan view of the same. Fig. 7 is a detail of hinge joint ring. Fig. 8 is a top plan view of neck. Fig. 9 is a cross-section of neck in line $y-y$ of Fig. 1. Fig. 10 is a detail view of one of the bottom sections. Fig. 11 is a plan view of cover of mold. Fig. 12 is a cross section of cover of mold.

Similar letters of reference indicate corresponding parts in the several figures.

Referring to the drawing; A designates a former for a cistern composed of an inverted cone-shaped bottom B having a central covered circular closure in its apex which, with

the bottom, is detachably seated in an opening formed centrally in a detachable building stand B² upon which the former or mold is built when the former or mold is located in the opening in the ground.

C designates a triangular bottom section of which a number are employed arranged in a circular series in the former or mold, the apices of which converge to the opening in the center of the former or mold. These sections are provided upon their edges with tongues and grooves d, and upon the inner faces are secured curvilinear blocks d', d², cleats d³ and small metallic clips d⁴, d⁵, d⁶, are also secured near the convex edges of the blocks d', d², which project slightly over said edges which are more clearly shown in the enlarged detail view in Fig. 10 of the drawings.

E designates a circular metallic detachable binding band by which the sections are bound together. This band is passed around the convex peripheral edges of the blocks d² and under the projecting portions of the clips d⁴ and d⁵, the meeting ends of which terminate in loops e, e'.

F designates a ratchet lever, the outer end of which is pivotally secured in the loops e, e' of the meeting ends of the band by means of pivots f, f, rigidly secured in said end of the lever, the outer end playing in a recess f² formed in a section of one of the circular pieces. The opposite free end of the lever F, is passed under one end of a short piece f², provided on its free end with a pin f' one of the edges of the lever F, being serrated for the purpose of engaging said pin. The other end of the piece f², is pivoted to the block d², of an adjacent triangular section C. G designates another and shorter ratchet lever, one end of which is similarly secured in the loops, g, g', of a smaller and inner circular band passed around the periphery of the blocks d' and under the metallic clips d⁴. H designates another and shorter piece or strip having one end secured to the block d' of an adjacent section C, the opposite end being left free and under which the free end of the ratchet lever G is passed so that the ratchet teeth of the lever G may engage a pin h secured in the free end of the lever H.

Three of these bottom sections at their outer or broader portions are hinged together as at i', i², to enable the ratchet mechanism to 105 110

remain intact when it is necessary to remove the sections in disassembling or removing the parts after the cistern is formed. Another of these bottom sections is hinged 5 as at L at its apex to a small centrally located disk to which the apices of the triangular sections C abut and at its outer or broader portion, a keeper or key L' is passed through an opening in the band E and also in a block L² to secure and release this at 10 this point.

M designates one of a multiple number of vertical curvilinear side sections of the former, and secured to the inner face thereof of near the top of said section is a curvilinear block m upon which is seated another curvilinear block m'. The block m has at one 15 end a beveled edge m³ as shown in Fig. 4. A short strip m⁴ is secured to the inner faces 20 of these sections and located at right angles to the blocks, and another piece m⁵ being secured to the inner face of the section M and located beneath these blocks, said piece supporting the blocks. Hinged to the ends 25 of block m' by means of hinges N, N', are two short beveled blocks N², N³. At one end of the block m is another small beveled block hinged to the under side and end of 30 said block as at n. These blocks, when the former or mold is assembled, form one of the rims of the same by fitting in corresponding recesses in adjacent strips and held detachably by buttons n', n², as clearly 35 shown in Figs. 5 and 6 of the drawings. A lower group of blocks forming the lower rim of the former are also secured to the inner face of the section M and are a duplicate of the upper group. The description of the upper group being already given it is not 40 thought necessary to again describe this group. Bands I⁴ are passed around the upper series of the blocks just described and are identical in construction to the band E, being provided with a similar ratchet lever 45 and keeper. Small metallic clips m² are secured to the upper sides of the blocks m', under which the bands I⁴ are passed.

P, designates the dome or cover section, which is formed in several detachable sections which rest upon the vertical curvilinear side sections, as shown in Fig. 1.

In Fig. 3 I have shown a bottom plan or inverted view of the cover of the former which is substantially a duplicate of the 55 bottom section, the exception being that several of the triangular shaped sections are not hinged as fastening means but buttons alone are used. This not being deemed an essentiality it is thought that the description heretofore given of the construction of the bottom section will answer for the cover section. Q designates the neck of the mold or former located over the open portion at the apex of the dome and which is composed 60 of an outer and an upper annulus q. and a

lower and outer annulus q'. These annuli are detachably secured to an inner and upper annulus R and an inner smaller and lower annulus R' by means of rods R², R³ and R⁴ having upper curvilinear ends passed 70 through openings in the annuli as clearly shown in Figs. 1 and 8. Within these annuli and disposed in circular series is a multiple number of vertical slats S, S', located 75 equi-distant from each other. The upper and outer annulus q is slit through and a latch T is formed of a short piece of metal which is secured upon the outer surface of the annulus q by which the annulus q may be opened or closed as occasion requires, a 80 staple T' being secured to the outer surface of the annulus q by which an opening formed in the end of the hinge allows the staple T' to pass through it for securing the meeting ends of the annulus q together. As 85 the fastening means for the inner and upper annulus R is a counterpart of the fastening means for the annulus q as shown in Figs. 7, 8 and 9 a further description of this feature of the invention is deemed unnecessary. 90

U designates a circular cover or mold for the neck of the body of the former or mold which is formed in two sections u and u' detachably secured together by means of a band V passed around the periphery of said 95 cover, and secured to this band V at one of the meeting ends of the two sections is a short strip of metal V' having an opening in one of its ends through which is passed a staple V² secured to the band which engages in the opening in one end of the strip V' and through which is passed a keeper not herein shown to hold the sections together. The cover or mold U, of the neck portion of the body of the former or mold 100 is located between the larger annuli q and q' and the upper and lower annuli R and R' and the underside thereof is projected onto the concrete or filling between these annuli. 105

In Fig. 7 I have shown an enlarged view 110 of one of the circular pieces and means for securing the two sections of the same together consisting of a narrow flat strip of metal W, in which is formed an eye W', bent around a small pivot W², centrally thereof, said strip being provided at one end with a slot w within which engages a 115 staple X, which secures the two ends of this circular section together, as clearly shown in Fig. 7 of the drawings.

The utility and manner of operating the improved mold or former will be readily understood. The entire device assembled as 120 illustrated in Fig. 1 is inserted into the opening formed in the ground, and the space between the outer surface of the mold and the wall of the ground opening is filled with cement, the bottom of the opening having been previously covered with cement. The neck portion of the mold is also cov- 125

ered with cement and after the cement has set or hardened an operator descends into the former and, by releasing the devices which secure the mold sections, permits the latter to be collapsed and removed separately through the opening in the mold neck. Thus it will be observed that the mold serves as a core around and upon which the completed cistern is formed.

10 Having fully described my invention, what I claim as new and desire to secure by Letters Patent is:—

15 1. A mold or former for cement or concrete cisterns, comprising a cylindrical body portion consisting of separable sections, means for detachably securing said sections together consisting of clamping bands and horizontally arranged serrated levers, a neck supported upon the upper end of the

body portion and consisting of concentric 20 annuli connected by curvilinear rods.

2. A mold or former for cement or concrete cisterns, comprising a body portion consisting of a series of vertically disposed sections, means for securing said sections together detachably, consisting of clamping bands and serrated horizontally operating tensioning levers for said bands, a bottom consisting of a series of triangular sections provided with securing cleats, and a neck 25 30 supported upon the upper end of said body portion.

In testimony whereof I affix my signature in presence of two witnesses.

GUSTAVUS A. WAGNER.
